JUICING MACHINE

Albert W. Gould, Loughman, Fla.

Application July 21, 1939, Serial No. 285,772

7 Claims. (Cl. 100—47)

This invention relates to machines for extracting fruit juices and more especially to that type of machine for extracting the juices of citrus fruits, wherein the fruit is split by a suitable knife and the two halves are thereafter subjected to pressing or squeezing action to expel the juices.

One important object of the invention is to provide a novel and improved form of extractor roll for such a machine.

A second important object of the invention is to provide novel means, acting in combination with such roll, to keep the roll free from accumulation of pulp and to clear the roll of the fruit juices.

A third important object of the invention is to provide a novel form of presser roll operating in conjunction with the extractor roll.

A fourth important object of the invention is to provide a novel arrangement of presser and extractor roll wherein provision is made for adjustment of the presser roll toward and from the extractor roll.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a view of the left-hand end of the machine showing the general construction thereof;

Figure 2 is a view of the right-hand end of the machine with certain of the parts omitted in order to better disclose other parts;

Figure 3 is an enlarged detailed view partly in elevation from the right-hand end and partly in section and showing the essentially novel arrangement of the knife and rolls, together with other associated parts;

Figure 4 is an enlarged detailed view of the means for adjusting the presser roll toward and from the extractor roll;

Figure 5 is a fragmentary detail to large scale showing the extractor roll, the wiping bar and the cleanout fingers;

Figure 6 is an enlarged detailed end view partly in section of the parts shown in Figure 4.

In the embodiment of the invention here shown there is indicated in general a frame 10. It is not deemed necessary to describe the exact construction of this frame since those parts

thereof having to do with the present invention will be hereinafter referred to. Supported adjacent this frame is an auxiliary frame 11, the inner end of the top of this auxiliary frame being carried by a bracket 12 attached to the main frame 10. The auxiliary frame includes a platform 13 whereon is mounted a motor 14. Supported at the front and rear of the frame 10 are brackets 15 whereon are mounted alined bearings 16 in which is journaled a knife shaft 17. Mounted on this knife shaft centrally between the front and rear sides of the frame 10 is a splitting knife 18, at each side of which is a circular shield 19 whereby fruit delivered to the knife is forced out of contact therewith so that the halves of the fruit drop onto downwardly inclined delivery chutes 20. On the shaft 21 of the motor 14 there is fixed a sprocket 22 which is connected by a chain 23 with a sprocket 24 fixed upon the shaft 17. Thereby operation of the motor 14 causes rapid rotation of the knife 18.

Also on the shaft 21 there is fixed a sprocket 25 which is connected by a chain 26 to a sprocket 27 on the drive shaft 28 of a reduction gearing, such as a worm or worm wheel gearing, the housing of which is shown at 29. It is not deemed necessary to show the construction of this gearing since the same is old and well known.

Suitably supported from the frame 10 is a shaft 30 which extends along the rear of the machine. On the shaft 30 is fixed a sprocket 31 which is connected by a chain 32 with a sprocket 33 on the driven shaft 34 of the reduction gearing held in the housing 29.

At the rear of the frame 10, and at the top thereof, there is provided a bracket structure 35 which supports bearings, one of which is shown at 36. Journaled in these bearings is a shaft 37 whereon is fixed a sprocket 38 which is connected by a chain 39 to a sprocket 40 fixed on the shaft 30.

Just below the shaft 17 the frame 10 includes a pair of frame members, one at each side, as indicated at 41. On these frame members are mounted bearings 42 spaced equally from the knife 18 toward the front and rear of the machine, and in these bearings are journaled shafts 43. The frame 10 carries a bracket 44 and on this bracket is mounted a pair of idler pulleys 45. On each of the shafts 43 is mounted a sprocket 46 and on the shaft 37 is mounted a further sprocket 47. A chain 48 runs downwardly from the sprocket 47, passes around one of the idler pulleys 45 and thence under the front sprocket 46, over the rear sprocket 46, back to the remaining

idler pulley 45 and up to the sprocket 47. By this means the shafts 43 are driven in opposite directions. Each of the shafts 43 has supported thereon a pair of elongated bars 49, the bars of each shaft being connected by rods 50, each rod being located at a respective end of the bar. The shafts 43 are so positioned that when rotating, the bars 50 work over the chutes 20 in a direction as indicated by the arrows in Figure 3 to cause 10 the halves of the split fruit to pass down the chutes 20.

Secured to each side of the frame 10 is a pair of plates 51 each having formed or welded thereon the bearing sleeves 52. Mounted rotatably 15 in the sleeves 52 are extractor roll shafts 53. On each of the shafts 53 is mounted a pair of extractor rolls indicated in general at 54. As best shown in Figure 5 each of these extractor rolls comprises a cylindrical body 55 having formed 20 therein a multiplicity of deep and narrow annular grooves 56 spaced longitudinally of the roll. Also extending from side to side of the machine, and suitably journaled to said sides, is a pair of presser roll shafts 57. Each of the 25 shafts 57 carries a presser roll 58 having a series of ribs 59 formed thereon, the ribs extending longitudinally of the roll and being parallel to each other.

In order to journal the shafts 57 so that the 30 presser rolls 58 may be adjusted toward and from the extractor rolls 54, there is provided at the front and rear of the frame and located at each side thereof, a bracket 59. On each of these brackets is supported a bearing 60 where- 35 to is pivoted a rock arm 61 in which a respective end of the shaft 57 is journaled. This rock arm 61 has its upper end curved outwardly as at 62. Mounted on the frame 10 in substantial alignment of the upper ends 62 of the rock arms are plates 63 through which passes the shank 64 of 40 an adjusting screw 65. The shank 64 carries on its outer end a hand wheel 66 for manipulation of the screw and the screw is prevented from moving longitudinally by means of collars 67 fixed thereto on opposite sides of the plate. A 45 yoke member or fork 68 is pivoted to the end 62 by a pivot 69 and this yoke member is provided with an internal threaded boss 70 wherein the screw 65 fits. It is to be noted that lost motion 50 will be provided at the pivot connection 69 to permit proper operation of the device.

With this construction, rotation of the screw 55 65 in one direction causes the presser roll 58 to approach the extractor roll, while rotation in the opposite direction causes the presser roll to move away from the extractor roll and thereby the degree of pressure on the split fruit during its passage between the rolls may be regulated.

On each of the shafts 57 there is fixed a 60 sprocket 71 and on the shaft 30 is a sprocket 72. Also there is supported on the frame an idler pulley 73. A chain 74 extends from the pulley 72 beneath the adjacent sprocket 71, over the idler 73, over the remaining sprocket 71 and back 65 to the sprocket 72. Also, on the shaft 30 is a sprocket 75 and on each of the shafts 53 is a sprocket 76. Opposite the shaft 30 the frame supports an idler pulley 77 and the chain 78 runs from the sprocket 75 to the idler 77, back 70 beneath one sprocket 76, over the other sprocket 76 and back to the sprocket 75.

By means of the arrangements just described the presser and extractor rolls are revolved in opposite directions, as can be seen by the arrows 75 in Figure 2.

In order to assist in feeding the fruit halves between the rolls and then push them downward there is provided a pair of shafts 79 which are journaled in the arms 61 and each of these shafts carries a pair of spaced discs 80 connected 5 by rods 81, there preferably being four of these rods.

In order to revolve the shafts 79 there is provided on each of these shafts a sprocket 82 which is connected by a chain 83 with the chain 10 84 mounted on the respective shaft 57. By this means rotation of the shaft 79 is in such direction, as shown by the arrows in Figure 3, that material passed from the chutes 20 is pushed down between the presser and extractor rolls. 15

In order to effect the separation of the juice from the rinds, seeds and most of the pulp, there is provided a wiper bar 85 having notches 85' wherein the ribs between the grooves fit which is supported by a plate 86 at each end, these plates 20 engaging on the sleeves 52 so that they do not contact with the shafts 53. This wiper bar rests against the face of the extractor roll and carries brackets or arms 87 which, in turn, carry clean-out bars 88 provided with fingers 89, each of 25 which extends into a respective slot substantially to the bottom thereof so that any material, such as pulp, which would tend to collect in the slots 56, is forced outwardly therefrom. Moreover, by the providing of the narrow slots 56, the juice 30 is trapped by capillary attraction in these slots and prevented from running down over the wiper bar, the function of the latter being to keep the outer part of the roll clear so that the juice can enter the slots. By an inspection of Figure 3 it 35 will be seen that the upper edge of the bar 85 engages the roll 54 substantially along the line of intersection of a plane connecting the axes of the shafts 53 and 57 with the periphery of the roll 54. Thus the upper edge of bar 85 is sub- 40 stantially at the nearest portions of the peripheries of rolls 54 and 58. It is to be observed that in the operation of the rolls 54 and 58, until the bar 85 is reached by the half fruit the squeezing effect is confined to the pulp of the 45 fruit and little or no squeezing effect is produced on the peel or rind. However, along the line of greatest approximation of the rolls 54 and 58 the peel or rind will be apt to be squeezed and the bitter oil expressed. Because of the presence of 50 the bar 85 practically none of this bitter oil will enter the slots of the roll 54 so that the desirable juice will not be contaminated but will be pure and sweet.

Secured to the outer face of each wiper bar is 55 a refuse chute 90 having a reenforcing rib 91, and on the under side of this downwardly inclined chute 90 is a stop plate 92 which serves to prevent any juice which may run down the under side of the chute 90 from passing beyond the 60 walls of a tank or receptacle 93 which is mounted at the bottom of the machine to receive the juice.

The fruit is fed to the knife in proper position for splitting by a V-shaped structure 94 at 65 the top of the machine, this structure including a pair of synclinal belts having suitable lugs thereon to convey the fruit.

In operation, the fruit is conveyed to the knife by these belts and the knife serves to split the 70 same, the halves passing down the chutes 20, being assisted in this operation by the action of the bars 50. After leaving the chutes the halves drop between the presser and extractor rolls and are pushed down therebetween by the 75

action of the bars 81. The juice is there extracted and enters the slots 56, from which it is expelled by the fingers 89 to drop into the receptacle 93. At the same time the skin or rind 5 passes down the refuse chutes 90.

When the half fruit passes between the extractor roll and the presser roll, the juice from the pulp cells is expressed into the grooves, while any oil forced from the skin or rind is pressed 10 against the surface of the presser roll, and because of the location of the wiper, there is no liability of the rind or any oil expressed therefrom becoming mixed with the juice expressed 15 from the pulp cells.

15 It will be noted that the belt arrangement is such that the extractor roll has a lower peripheral speed than the presser roll and yet, by reason of the peculiar construction, the extractor roll is run at a low speed, for instance, about 20 60 R. P. M.

It is obvious that minor changes may be made in the form and construction of the invention without departing from the material spirit thereof. It is not, therefore, desired to confine the 25 invention to the exact form herein shown and described, but it is desired to include all such as properly come within the scope claimed.

Having thus described the invention, what is claimed as new is:

30 1. In a fruit juicing machine for expressing the juice from fruit with the skin on the latter, an extractor roll comprising a cylindrical body provided with a multiplicity of spaced circumferential juice receiving grooves, means for rotating the extractor roll, a squeezing roll extending parallel with and adjacent the extractor roll, the rolls being spaced apart sufficiently for the passage of the skin and pith of the fruit, means for delivering fruit sections between the extractor 40 roll and squeezing roll with the pulp surface thereof to be engaged by the periphery of the extractor roll, means for rotating the extractor roll and the squeezing roll in opposite directions to squeeze the juice from the pulp of the fruit, 45 releasing and deflecting means engaging the peripheral surface of the extractor roll at the most proximate point of maximum expressing to remove the accumulated pulp and pulp juice and deflecting the skin away from the extractor roll, 50 means for conveying the skin and pith from the releasing and deflecting means, a plurality of scraper fingers fitting in the grooves of the extractor roll, said fingers engaging the bases of the grooves and located below the upper edge 55 of the releasing and deflecting means, whereby to remove accumulated pulp juice in the grooves of the extractor roll, and means independent of the skin and pith conveying means for receiving the expressed fruit juice.

60 2. In a fruit juicing machine for expressing the juice from fruit with the skin on the latter, an extractor roll comprising a cylindrical body provided with a multiplicity of spaced circumferential juice receiving grooves, means for rotating the extractor roll, a squeezing roll extending parallel with and adjacent the extractor roll, the rolls being spaced apart sufficiently for the passage of the skin and pith of the fruit, means for delivering fruit sections between the 65 extractor roll and squeezing roll with the pulp surface thereof to be engaged by the periphery of the extractor roll, means for rotating the extractor roll and the squeezing roll in opposite directions to squeeze the juice from the pulp of the fruit, 70 including means for rotating the squeezing roll 75

ing roll faster than the extractor roll, means engaging the peripheral surface of the extractor roll at the most proximate point of maximum expressing to deflect the skin from the peripheral surface of the extractor roll at or about the time 5 the juice squeezing action commences, whereby to avoid substantially any skin particles being mixed with the fruit juice expressed in the grooves of the extractor roll, means for conveying the skin from the skin directing means, a 10 plurality of scraper fingers fitting in the grooves of the extractor roll below the upper edge of the skin removing means, whereby to remove accumulated pulp juice in the grooves of the extractor roll, and means independent of the skin 15 conveying means for receiving the expressed fruit juice.

3. An extracting mechanism for juicing machines, including cooperating extracting roll and presser roll, means for operating the rolls to 20 cause their proximate cooperating peripheral surfaces to move in the same direction, the rolls being spaced apart to compel an approximately complete juice extracting pressure on any fruit element passing between the rolls, means for 25 delivering a halved fruit element between the rolls, with the pulp side in contact with the extractor roll, the extractor roll being formed with juice receiving channels to direct the juices extracted from the pulp of the fruit element circumferentially of the extractor roll to a point of discharge, the presser roll being peripherally fluted to cooperate with the rind of the fruit elements during the extracting operation, and means cooperating with the extractor roll at substantially 30 the point of maximum pressure between the rolls to deflect any juices extracted from the pulp of the fruit element into the channels of the extractor roll, and to prevent any oil extracted from the rind of the fruit element 35 under the pressure between the rolls from reaching the fruit channels of the extractor roll.

4. An extracting mechanism for juicing machines, including cooperating extracting roll and presser roll, means for operating the rolls to 40 cause their proximate cooperating peripheral surfaces to move in the same direction, the rolls being spaced apart to compel an approximately complete juice extracting pressure on any fruit element passing between the rolls, means for delivering a halved fruit element between the rolls, with the pulp side in contact with the extractor roll, the extractor roll being formed with juice receiving channels to direct the juices extracted from the pulp of the fruit element circumferentially of the extractor roll to a point of discharge, the presser roll being peripherally fluted to cooperate with the rind of the fruit elements during the extracting operation, and a wiper bar 45 cooperating with the extractor roll at substantially the point of maximum pressure between the rolls, said wiper bar being wholly imperforate for its full length immediately below its cooperation with the extractor roll to thereby completely segregate the juices extracted from the pulp 50 and delivered to the channels of the extractor roll and any oil extraction from the rind of the fruit element which may be extracted through the cooperation of the presser roll.

5. An extracting mechanism for juicing machines, including cooperating extracting roll and presser roll, means for operating the rolls to cause their proximate cooperating peripheral surfaces to move in the same direction, the rolls being spaced apart to compel an approximately 55 60 65 70 75

- complete juice extracting pressure on any fruit element passing between the rolls, means for delivering a halved fruit element between the rolls, with the pulp side in contact with the extractor roll, the extractor roll being formed with juice receiving channels to direct the juices extracted from the pulp of the fruit element circumferentially of the extractor roll to a point of discharge, the presser roll being peripherally fluted to cooperate with the rind of the fruit elements during the extracting operation, and means arranged between the rolls to completely segregate the juices extracted from the pulp from any oil extraction from the rind of the fruit element, incident to the operation of the presser roll, whereby the juice of the fruit element and the oil of the rind cells are automatically separated for independent discharge.
6. An extracting mechanism for fruit juicing machines, including cooperating elements between which a divided section of citrus fruit is subjected to a juice extracting operation, one of said elements having circumferential recessions cooperating with the pulp side of the divided fruit and the other of said elements cooperating with the rind side of said fruit, the element cooperating with the pulp side of the fruit directing the

extracted juices in one direction, the element co-operating with the rind side of the fruit carrying incidentally extracted oils in another direction, and means arranged in that relation to the elements as will prevent any co-mingling and maintain substantially complete separation of any extracted juices from the pulp and incidental oils extracted from the rind. 5

7. Means for expressing juice from citrus fruit and at the same time substantially separating 10 skin oil, comprising a slotted element over the surface of which the cut face of halved fruit passes, a ribbed squeezing roll spaced from the slotted element to engage the outer surface of the skin of the cut fruit, means for rotating the 15 ribbed roll, means for feeding cut sections of fruit to and between the slotted element and the ribbed roll, and a flat plate located adjacent the slotted element and between same and the ribbed roll, whereby when a half fruit section is passed 20 between the slotted element and the ribbed roll juice from pulp cells will be expressed therefrom and through the slots in one direction, and the skin, pith and any extracted skin oil will be carried away in the opposite direction. 25

ALBERT W. GOULD.
